UNITED STATES PATENT OFFICE.

MIGUEL GIL CASARES, OF SANTIAGO, SPAIN.

METHOD OF AND APPARATUS FOR RECORDING ARTERIAL PULSATIONS.

1,413,389.

Specification of Letters Patent. Patented Apr. 18, 1922.

Application filed July 25, 1919. Serial No. 313,221.

To all whom it may concern:

Be it known that I, MIGUEL GIL CASARES, a subject of the King of Spain, and a resident of Santiago, Spain, have invented certain new and useful Improvements in Methods of and Apparatus for Recording Arterial Pulsations.

This invention relates to an improved method of and apparatus for recording arterial pulsations, such apparatus being of the class commonly known as sphygmographs, and more especially to an instrument of that character which I have herein designated as a cinephotopalograph, the object of the invention being to provide an instrument by means of which circulation phenomena in different parts of the body may be simultaneously recorded photographically on a single sensitized strip during movement of such strip.

With the foregoing and other objects in view, which will appear as the description proceeds, the invention consists in the novel features of construction and combination of parts which will be more fully described hereinafter and particularly pointed out in the claims.

In the drawings accompanying and forming part of this specification,

Figure 1 is a partly sectional side elevation of the instrument proper;

Fig. 2 illustrates in side elevation the funnels and portions of the flexible attaching tubes, one of said funnels and its tube being shown in section;

Fig. 3 is a perspective view illustrating the complete instrument; and

Fig. 4 illustrates a development of the photographic record produced by the instrument.

The same characters of reference designate the same parts in the different figures of the drawings.

The method and apparatus herein described are based upon the following two fundamental facts:

(a) By fitting to the end of a small funnel a flexible tube and placing the opposite end of said tube in communication with a glass tube of small diameter having a portion thereof bent into U-shape and in which a small quantity of a suitable liquid, such for instance as ether, acetone, or even water has been placed, and then carefully applying the open end of the funnel to certain parts of the body where the pulsations

of the heart and arteries and the movements of the veins may be noted, the pulsative phenomena are freely transmitted to the liquid in the U-shaped tube.

(b) The physical peculiarities presented by the manometrical tube can be recorded by projecting through the use of luminous rays a silhouette of such tube on a sensitized strip.

Referring to the drawings, 2 designates a supporting base or stand, preferably of wood, to which is secured a bracket 3 for supporting a source of light, shown herein as an electric lamp 11. Mounted on the base 2 is a stationary cylindrical casing 5, having a suitable top closure 7 and provided, in its side wall, with a plurality of vertically alined slits or openings 6, shown herein as three in number, one of said slits being shown in full lines and the others in dotted lines in Fig. 1.

Within the casing 5, concentric therewith, is mounted for rotation a second cylinder 8, the rotation of which may be produced by a suitable clockwork mounted therein, said clockwork being indicated in a general way at A. The cylinder 8 is adapted to carry on its periphery a strip of sensitized paper or film, any suitable means being provided for holding the film in position on the cylinder. Means may also be employed for varying the speed of rotation and for automatically stopping such rotation at the end of a complete revolution.

Supported on the base 2 and the casing 5, are a plurality of transparent tubes 9, each having a U-shaped portion, one leg 10 of which is in position to close one of the slits 6 in the casing 5, and suitably carried by the bracket 3 in alinement with the legs of the tubes is a source of light, such as an electric lamp 11. Communicating with the outer end of each of the tubes 9 is a flexible tube 12, carrying at its opposite end a funnel 13.

At the lower part of the casing 5 is provided means for indicating photographically periods of time, preferably one-fifth of a second. This means in the present instance comprises a slidable member 14 adapted to uncover alternately the upper and lower ends of an opening in the casing 5 to expose a portion of the film to the light. The member 14 may be actuated by means of a rod and pin connection with a pulley or wheel 15, which in turn may be rotated

by means of a clockwork (not shown) carried within the base 2, and so adjusted that the slide will move in one direction or the other every one-fifth of a second.

5 From the foregoing, it will be seen that if a small quantity of liquid such as ether is placed in the bent portion of the tubes 9, and the funnels 13 applied to the body of a patient, as hereinbefore referred to, the pulsations will be freely transmitted to the liquid, and if the cylinder 8 carrying the sensitized strip is set in motion, while the light is turned on so as to illuminate the transparent legs 10 of the tubes 9, the strip will receive an impression through the slits 6 in the casing 5. It will be found that each of such impressions comprises three clearly distinct zones, these zones corresponding to the liquid (the part which is most highly impressed), the clear border (al menisco) and the air (intermediate impression).

In Fig. 4, I have illustrated a development of the film. In this figure, the two lower impressions, each comprising the zones *a*, *b* and *c*, represent impressions without pulsation, while the upper impression, comprising the zones *d*, *e* and *f*, represents an impression made when the funnels are applied to a pulsating region of a patient's body. The white bands *g* between the impressions are the portions of the film protected from the light by the opaque portion of the casing 5 between the ends of adjacent slits 6. The broken line *h* indicates the impressions made by reason of the periodic movement of the slide 14.

Each of the funnels 13 is provided in its wall with a small aperture 16, so that when the funnel is applied to the body of the patient, any undesirable air compression in the funnel and tube is avoided. The operator may close these openings with the tips of his fingers while forming the impressions, and may uncover the openings before removing the funnels from the body, so as to avoid the aspiration of the ether toward the flexible tubes.

While I have described in detail the structure herein illustrated, it is to be understood that I do not thereby limit my invention to the precise features of construction shown, as I am aware that many mechanical changes and modifications may be made therein without departing from the spirit and scope of

the invention as set forth in the appended claims.

55

Having thus described my invention, what I claim is:

1. In an apparatus for physiological and clinical examination for noting the pulse variations of the circulatory system, the combination of a casing provided with a vertical slit, a rotatable member within said casing and adapted to carry a sensitized strip adjacent to said slit, a U-shaped transparent tube supported outside of said casing and having a leg in position to close said slit, said tube carrying a liquid in the bent portion thereof, a source of light disposed in position to diffuse its rays through said legs and slit and on to said sensitized strip thereby to generate on the strip a reception field containing three distinct impressions corresponding respectively to the liquid in the tube, the meniscus of said liquid and the air in the tube, and a pulsation transmitting tube attached to said U-shaped tube.

2. In an instrument of the class described, the combination of a casing having a plurality of slits therein in vertical alignment, a rotatable member within said casing adapted to carry a sensitized strip adjacent to said slits, a plurality of U-shaped transparent tubes supported outside of said casing and each having a leg in position to close one of said slits, and carrying a liquid in the bent portion thereof, a source of light disposed in position to diffuse its rays through said legs and slits and on to said sensitized strip thereby to generate on the strip three separate reception fields, each containing three distinct impressions corresponding respectively to the liquid in the tube, the meniscus of said liquid and the air in the tube, and a separate pulsation transmitting tube attached to each of said tubes and adapted to be applied to different portions of a body for recording on said sensitized strip a common picture of the pulsations at such different portions at the same moment.

In testimony whereof I have signed my name to this specification in the presence of two subscribing witnesses.

MIGUEL GIL CASARES.
